Inventor:
W. Norton Cook.

United States Patent Office.

W. NEWTON COOK, OF GRAND RAPIDS, MICHIGAN.

Letters Patent No. 95,880, dated October 19, 1869.

IMPROVED SPRING-BED BOTTOM.

The Schedule referred to in these Letters Patent and making part of the same.

Be it known that I, W. NEWTON COOK, of the city of Grand Rapids, in the county of Kent, and State of Michigan, have invented a certain new and useful Improvement in Spring-Bed Bottoms; and I do hereby declare that the following is a full and exact description thereof, reference being had to the accompanying drawings, and to the letters of reference marked thereon.

In the drawings—

Figure 1 is a perspective view of the spring-bed bottom.

Figure 2 is a longitudinal section, through the centre of the same.

Figure 3 is a transverse central section of the same, showing the spring-bed bottom in its place on the bedstead.

Figure 4 is a perspective inside view, showing one end of a side rail of the ordinary bedstead in common use.

The nature of my invention consists—

First, in providing the bed-bottom with an elastic guide-bar, whereby lateral motion of the bed is controlled, and a central and horizontal position of the upper frame preserved:

Second, in constructing the upper and lower frames of the bed-bottom of unequal length and width; for the purposes of maintaining a fixed position on the bedstead, affording a suitable space for the bed clothes to fold in between the bed and bedstead, and for rendering the use of slats for the support of the bed-bottom unnecessary.

Third, in constructing the bottom frame of the bed-bottom, with the side bars of the same, projecting beyond the outermost cross-bars, for the purpose of the more readily fitting the bed-bottom to any of the ordinary bedsteads in common use, by removing so much of the projecting ends as may become necessary.

In order to enable others skilled in the art to make and use my invention, I will now proceed to describe its construction and operation.

A, figs. 1, 2, and 3, represents a rectangular frame, of wood, covered with canvas, b, fig. 1, and of such dimensions as to afford a suitable space for the bed-clothes to fold in between the sides of the frame and side rails E of the bedstead, as shown at d, fig. 3.

B, figs. 1 and 3, represent a rectangular frame, made wider and shorter, than the frame A, and of such size as to fit in the space occupied by the slats in the common bedstead, so that it may rest on the ordinary cleats f, fig. 3, of the side rails E, always provided for the support of the slats.

The two outermost cross-bars of the bottom frame B are placed a short distance inside of the end of the side bars, as shown at g, fig. 1, for the purpose of facilitating the fitting of the bottom to any of the

bedsteads in common use, in the manner following, viz:

The side rails of such bedsteads are attached to the head and foot-posts by means of metallic hooks, shown at m, fig. 4.

These hooks are made fast to the side rails E, by means of stays or cleats i, which latter vary in width according to the custom of different makers, so that the space between them, on the side rails E, varies in length.

To fit this bed-bottom to any of these bedsteads, all we have to do is to simply cut off the required portion of the projecting ends g, fig. 1.

Spiral springs, of any form, either helical or conical, are placed in suitable supports, made fast to the frame B, and their tops kept in position by the usual method of cross-tying, to the frame A, with twine.

A guide-bar, C, of equal length with the top frame A, passes on the under side and lengthwise of the bottom frame B, and is fastened to the latter at suitable points, equidistant from its centre, by screws h, fig. 2.

The bar C is fastened to the top frame A at its ends, by means of bolts and thimbles D D.

Straps of leather or cloth, e e, fastened at either end to each frame, serve to confine the frames to any desirable distance apart, which should not be greater than that fixed by the bolts and thimbles D D, as shown at e e, fig. 1.

In using this bed-bottom, when the weight of the necessary bedding is placed upon it, the springs a yield, carrying the guide-bar downward, so that when in use, no contact is had between it and the bottom frame, except at its points of support.

If greater weight be at any time placed on one corner, or one side of this bed than on another part, the effect will be to slightly twist the guide-bar, which, by virtue of its elasticity, acting in unison with the springs a a a, at once returns to its normal form and position the moment the unequal pressure is withdrawn.

One or more of these guide-bars may be used, if desired, their purpose being solely that of controlling the lateral motion caused by unequal pressure upon different parts of the bed, and to insure an upright position of the spiral springs, and consequently a central and horizontal surface of the bed so soon as any temporary weight is removed.

The advantages claimed to be secured by the use of this bed are many and obvious:

First, lateral motion, which has been found to be most destructive of all kinds of spring-beds, is effectively controlled, and by a very simple and cheap device.

Second, it dispenses with the use of slats alto-

gether, and hence does away with the noise, and extra trouble, and expense connected with their use.

Third, all its parts are simple in construction, cheap, and not liable to get out of order.

Fourth, it is free from noise, there being no levers or fulera to cause squeaking, nor sliding of spring-slats, or springs chafing each other.

Having thus described my invention,

What I claim, and desire to secure by Letters Patent of the United States, is—

The combination of the guide-bar C and frames A and B, bolts and thimbles D, springs *a a a a*, and canvas *b*, when constructed and used substantially as and for the purposes specified.

In testimony that I claim the foregoing, I have hereunto set my hand, this 9th day of April, 1869.

W. NEWTON COOK.
